UNITED STATES PATENT OFFICE.

ALBERT F. DAUM, OF PITTSBURGH, PENNSYLVANIA.

FUSE.

1,102,981.

Specification of Letters Patent.

Patented July 7, 1914.

Continuation in part of application Serial No. 702,599, filed June 8, 1912. This application filed March 24, 1913, Serial No. 756,544. Renewed February 24, 1914. Serial No. 820,662.

To all whom it may concern:

Be it known that I, ALBERT F. DAUM, a citizen of the United States, and residing at Pittsburgh, in the county of Allegheny and 5 State of Pennsylvania, have invented certain new and useful Improvements in Fuses, of which the following is a specification.

My invention relates to improvements in fuses, and has for its object to provide a 10 construction by means of which the fuse element is prevented from being cut-off at its point of exit from the end plugs or other support; to provide a structure in which the contact with the end cap is made in the 15 form of a wiping contact; to provide a structure in which the support may be yieldable; and to provide a construction which is simple and efficient in operation, durable in construction, and which can be made at 20 a relatively low cost.

To these and other ends, the nature of which will be readily understood as the invention is hereinafter disclosed, said invention consists in the improved construction 25 and combination of parts hereinafter fully described, illustrated in the accompanying drawings, and particularly pointed out in the appended claims.

In the drawings, in which similar reference characters indicate similar parts in 30 each of the views:—Figure 1 is a longitudinal sectional view of a portion of a refillable fuse showing one way in which my present invention may be applied. Figs. 35 2, 3, 4, 5, 6, and 8 are similar views showing various modifications of the invention. Fig. 7 is a face view showing a preferred form of support where the fuse element is in the form of a strip, this form of support 40 being shown in connection with Fig. 6. Figs. 9 and 10 are detail views of a resilient support for the fuse element. Fig. 11 is an end view of the form shown in Fig. 1 with the end cap removed.

45 One of the essential features for efficiency in a fuse and especially in refillable fuses, is the provision of a good contact between the fuse element and the end cap, and my ex-

perience has shown that to secure the best efficiency, this contact should be provided 50 by "wiping" the end cap over the fuse element. Where, however, as in refillable fuses, the end cap is threaded on to the fiber shell, the giving of this wiping contact has the effect of flattening the fuse element itself, 55 and where the fuse element is of small cross section, such, for instance, as is provided in telephone fuses or fuses necessitating the use of fuse wire of substantially the smallest gage, this flattening becomes a serious 60 factor, by reason of the liability of practically cutting off this wire at its point of exit from the supporting member through which it extends, the flattening of the wire beyond that point not materially affecting 65 the conducting qualities, since the cross-sectional area of the wire will remain but in a different form.

My present invention provides for practically insuring against cutting wire at this 70 point by increasing the distance between the opposing members between which the element is carried after passing beyond the fiber, this increase being provided in any suitable manner, but preferably by flaring 75 the end plug or member so as to increase the distance in the vicinity of the opening to which the fuse element extends. In the drawings, I have shown various forms of such end members. For instance in Fig. 1, 80 this end member, indicated at 10, is in the form of a washer which abuts against the end of the shell of insulating material 11. In use, the washer is slightly dish-shaped, the drawings illustrating the amount of depression for a large-sized fuse wire. It will 85 be understood that where the fuse wire is of relatively small gage, the amount of depression will be relatively smaller.

As will be readily understood, the threading of the end cap 12 on to the shell 11, will 90 cause the fuse element, indicated at 13, to be flattened when the threading has caused pressure to be applied on the fuse wire. By reason of the particular shape, this flattening 95 will take place first adjacent the outer

periphery of the washer, and as the pressure is increased, this flattening will be gradually carried toward the center of the washer, but as will be readily understood, a movement of the end cap sufficient to cause the outer edge of the washer to contact with the end cap will still leave a distance between the face at the center of the washer and the end cap, which distance will not be decreased by any additional pressure that may be placed on the end cap, so that there will always remain a cross-section thickness equal to this distance. There are several particular advantages due to this particular arrangement; for instance, the flattening effect is provided from the point of greatest distance from the center, always leaving the greatest amount of fuse metal at the center and in position to insure a positive contact with the cap; another advantage lies in the fact that should the end cap be threaded to provide a contact with the washer, the metallic contact thus provided is in a thin line adjacent the periphery of the end cap and removed from the point where the fusible metal is located, thereby greatly decreasing any possibility of a fusing of the washer to the end cap, and since the end cap is preferably provided with openings, the heat generated in the blowing of the fuse will quickly dissipate without providing a fusing of the cap and washer.

The end plugs may be of any desired type, the washer form shown in Fig. 1 being preferred owing to its relative inexpensive cost of manufacture. The other forms of such plugs or supports are shown in Figs. 3, 4, and 5, these plugs or supports extending into the fiber shell, Fig. 3 showing the member 10 as having a smooth peripheral face, while Fig. 4 shows a somewhat similar structure with the plug threaded to the shell; Fig. 5 shows a modification in the shape of a plug by means of which it may be made slightly resilient so as to provide for the expansion and contraction of the shell without affecting the fuse contact with the end cap, the slight resiliency of the member producing this effect. In Fig. 6, I have shown a somewhat similar arrangement of support where the fuse element is in the form of a strip, the support 10^a in this instance, preferably having lateral groove like depressions into which the fuse element is bent, as in Fig. 6, thus providing a depressed portion or portions acting similar to that referred to in connection with Fig. 1, the flattening of which is indicated somewhat in Fig. 11. I may also provide a resilient support, either by the use of a spring member 14 between the end of the shell and the washer 10, the latter having the dish-shaped feature, or I may form the spring member itself with a dish-shaped end, as shown in Fig. 10, in

which case the member will form the support, the washer being dispensed with. In each of these forms however, the outer face is formed dish-shaped or depressed about the point of exit of the fuse element producing a substantially similar effect to that produced by the washer of Fig. 1.

An alternative form of construction is illustrated in Fig. 2 in which the end cap has its inner face dish-shaped to provide for a somewhat similar operation, the member 10 in such case having either a straight face or a dish-shaped face.

While I have herein shown and described several ways in which my invention may be carried into effect, it will be readily understood that changes and modifications therein may be required or desired in use, and I desire to be understood as reserving the right to make any and all such changes and modifications as may be required or desired, in so far as the same may fall within the spirit and scope of the invention as expressed in the accompanying claims.

Having thus described my invention, what I claim as new is:—

1. In a fuse, a shell, a member through which the fuse element extends, and an end cap adapted to contact with the element, said cap and member having opposing element-contacting faces relatively shaped to provide an increase of distance therebetween at the point of exit of the element from said member, whereby relative movement of the end cap and member to provide a wiping contact will be least effective to change the cross-sectional area and form of the element at such point of exit.

2. In a fuse, a shell, a member through which the fuse element extends, an end cap adapted to contact with the element, said cap and member having opposing element-contacting faces relatively shaped to provide an increase of distance therebetween at the point of exit of the element from said member, whereby relative movement of the end cap and member to provide a wiping contact will be least effective to change the cross-sectional area and form of the fuse element at such point of exit, said distance increase being gradual from a point approximating the periphery of the member.

3. In a fuse, a shell, a member having a substantially central opening through which the fuse element is adapted to extend, and an end cap adapted to contact with the fuse element, said member having a face depressed at the point of element exit, said end cap having its inner face shaped to cooperate with the depressed face of said member to provide a space between said faces at and decreasing in depth away from the point of exit of the element.

4. In a fuse, a shell, a member having a

substantially central opening through which the fuse element is adapted to extend, and an end cap adapted to contact with the fuse element, said member having a face depressed at the point of element exit, said end cap having its inner face shaped to co-operate with the depressed face of said member to provide a space between said faces at and decreasing in depth away from

the point of exit of the element, said member including a yieldable support.

In testimony whereof I affix my signature in presence of two witnesses,

ALBERT F. DAUM.
